Primary Examiner—Ted Shooman*Assistant Examiner*—Mitchell I. Siegel*Attorney, Agent, or Firm*—Westman, Champlin & Kelly, P.A.[57] **CLAIM**

The ornamental design for an acrylic pool cue, as shown and described.

DESCRIPTION

FIG. 1 is a side elevational view of a acrylic pool cue, embodying my new design, all other side being identical;

FIG. 2 is a left end elevational view thereof;

FIG. 3 is an enlarged fragmented side elevational view of the tip portion of the acrylic pool cue for clarity of illustration; and,

FIG. 4 is an enlarged right end elevational view thereof.
